CLAIM

The ornamental design for an engine recoil handle, as shown and described.

DESCRIPTION

FIG. 1 is a side perspective view of the engine recoil handle according to a first embodiment of the present design;

FIG. 2 is a top plan view for an engine recoil handle assembly as shown in FIG. 1;

FIG. 3 is a bottom plan view for an engine recoil handle as shown in FIG. 1;

FIG. 4 is a right side elevation view for an engine recoil handle as shown in FIG. 1;

FIG. 5 is a left side elevation view for an engine recoil handle as shown in FIG. 1;

FIG. 6 is a rear elevation view for an engine recoil handle as shown in FIG. 1; and,

FIG. 7 is a front elevation view for an engine recoil handle as shown in FIG. 1.
